INVENTOR

UNITED STATES PATENT OFFICE.

EDWIN S. BOYER, OF PLAINFIELD, NEW JERSEY, ASSIGNOR TO AMERICAN HARD RUBBER COMPANY, OF HEMPSTEAD, NEW YORK.

DESIGN FOR A STORAGE-BATTERY JAR.

Application filed May 9, 1925. Serial No. 13,387. Term of patent 3½ years.

To all whom it may concern:

Be it known that I, EDWIN S. BOYER, a citizen of the United States, residing at Plainfield, in the county of Union and State of New Jersey, have invented a new, original, and ornamental Design for Storage-Battery Jars, of which the following is a specification, reference being had to the accompanying drawing, forming part thereof.

The figure is a perspective view of the battery jar, showing my new design.

I claim:

The ornamental design for a storage battery jar, as shown.

EDWIN S. BOYER.
